UNITED STATES PATENT OFFICE.

EVERETT C. LEWIS, OF SEEKONK, MASSACHUSETTS, ASSIGNOR TO UNIVERSAL WINDING COMPANY, OF PORTLAND, MAINE, A CORPORATION OF MAINE.

WINDING-MACHINE.

1,126,039.

Specification of Letters Patent.

Patented Jan. 26, 1915.

Application filed January 25, 1912. Serial No. 673,293.

To all whom it may concern:

Be it known that I, EVERETT C. LEWIS, a citizen of the United States, residing at Seekonk, in the county of Bristol and State 5 of Massachusetts, have invented certain new and useful Improvements in Winding-Machines, of which the following is a specification.

My invention relates to improvements in 10 winding machines and consists particularly of a novel arrangement of mechanism for releasing and doffing the completed cop or package from the winding spindle.

The object of my improvement is to provide 15 means for utilizing the power which drives the machine to force the package off from the spindle, so that the doffing may be done more easily and expeditiously, and without danger of injury to the package or 20 the material therein.

The invention is fully set forth in the following specification, illustrated by the accompanying drawings, in which:—

Figure 1 is a plan view of a winding machine, showing my new device applied thereto; Fig. 2, a front elevation of the same, part sectional on the line X—X of 25 Fig. 1; Fig. 3, an end elevation, looking in the direction indicated by the arrow a, Fig. 30 1; Fig. 4, a sectional view of the spindle bearings and cop-tube, taken longitudinally, and illustrating the manner of releasing the tube and doffing the package.

My invention is particularly adapted for 35 use on winding machines employed for winding cord, twine, rope and other heavy and strong materials. It is the general practice to wind such materials into relatively large packages for commercial purposes and the cheapest and most practical 40 form of support for such a package is the well known paper or fiber cop-tube, so-called. The cop-tube is usually held in the winding machine on a rotating mandrel or 45 spindle extending through it and as the layers of winding are built up to form the package the tube is subjected to great pressure, owing to the constriction of the coils which are laid on under heavy tension. 50 This constrictive action of the winding causes the tube to contract and bind on the

mandrel to such an extent that it is often a difficult matter to get it off, and frequently the package will be broken down and damaged in attempting to doff it. My new invention provides for utilizing the power of 55 the machine for forcing the cop-tube off the mandrel and thereby the doffing can be accomplished with greater ease and despatch and without danger of injury to the 60 package.

Referring first to Figs. 1 and 2, B designates the frame of the winding machine which is provided with bearings b, b' for the main driving shaft C, and opposite 65 bearings b², b³ for the traverse-cam shaft D. The shaft C is hollow, as shown in Fig. 2, and carries the belt pulleys E and E'. The pulley E is held fast on the shaft C by the set-screw e and serves to operate the whole 70 machine from the power transmitted through a suitable driving belt, not here shown. The pulley E' is adapted to rotate free on the shaft C between the hub of the pulley E and the bearing b and serves as 75 an idler on to which the belt is shifted when it is desired to arrest the operation of the machine.

The shaft C is formed at one end with a flange c abutting the end of the bearing b' 80 to take the thrust of the shaft in one direction, and a pulley F, secured to the shaft by a set screw f with its hub abutting the opposite end of the bearing b' prevents longitudinal movement of the shaft C in the 85 opposite direction. The pulley F is connected to a pulley G on the shaft D by a belt g to adapt the two shafts to rotate together. An adjustable idler-pulley H is arranged to bear on the top of the belt g between the two pulleys F, G to keep the belt 90 tight and prevent slippage. Preferably the pulley F is of the expandable type, now well known in the art, to provide for adjustment of its diameter so that the speed of the two 95 shafts can be varied in relation to each other to regulate the spacing of the coils of winding; but as this feature of the machine forms no part of the present invention it will not be described in detail.

Mounted on the end of the shaft D and 100 rotated thereby is a screw-shaft or cam J

having a double, helical groove *j* formed in its periphery. A carriage or slide *K* is fitted to the cam *J* and adapted to slide back and forth thereon, being reciprocated by a shoe or runner *k* which engages with the cam-groove *j*. The slide *K* has an arm or extension *k'* carrying a bushing *k²* which slides on a rod *O* supported on an overhanging portion of the frame *B* of the machine, parallel with the axis of the cam *J*. An arm *L* which serves as a twine-guide is formed with a forked end *l* straddling the extension *k'* and pivoted on the bushing *k²*. The arm *L* is provided with rolls on grooved pulleys *l'* and *l²* over which the twine *t* draws as it leads to the winding spindle, the tension on the material acting to keep the end *l²* of the guide-arm bearing on the winding. The guide-arm *L* is caused to traverse the winding spindle through the reciprocating motion imparted to the slide *K* by the cam *J* and as the package increases in diameter the arm *L* swings on its pivot to allow the guiding end *l²* to recede from the spindle.

The winding spindle or mandrel *S* which supports the cop-tube *x* on which the winding is performed is constructed as a telescopic extension of the hollow shaft *C*, being fitted to the bore of the latter and adapted to slide longitudinally therein, see Fig. 2. At the outer end of the shaft *C* is secured a sleeve or bushing *c²* which serves to locate the cop-tube *x* in position on the spindle *S* and also acts as a pusher to force the tube off when the spindle is retracted, as more fully explained hereinafter. During the winding operation of the machine the spindle *S* is in a forward position, as shown in Fig. 1, and its outer end is supported by an outboard bearing arranged as now described: A bracket *B'* extends from the side of the main frame *B* of the machine and projecting from the end thereof is an arm *B²*, see Fig. 1. The arm *B²* is preferably supported at its end by a rod *u* reaching to the floor, see Fig. 2, and is formed with a bearing *b⁴* in which a bushing *M* is adapted to rotate. Adapted to rotate with the bushing *M* and arranged to slide longitudinally therein is a "live" spindle *S'* having its axis in line with that of the spindle *S* and serving as an extension thereof.

The spindle *S'* is reduced in diameter at *s* throughout a portion of its length and again at its end and carries a hand-knob *N* secured to this end by a transverse pin *n*. The bushing *M* is formed with a flange *m* abutting the inner face of the bearing *b⁴* and a cap or collar *m²* is fastened to its opposite end and bears against the outer face of the bearing so that the bushing is held from longitudinal movement. Preferably, the cap *m²* is secured to the bushing *M* by screws *o*, *o* which are formed with extensions reaching clear through the bushing

and engaging grooves or splines *s'* in the reduced portion *s* of the spindle *S'*. Between the screws *o* and the shoulder *s²* of the spindle *S'* is a coiled spring *p* which serves to normally maintain the end of the spindle *S'* projected from the bushing *M* in the position illustrated in Fig. 2. This end of the spindle *S'* is provided with an axial hole *s³* and formed with radially disposed ratchet teeth *s⁴*. The opposing end of the spindle *S* is also formed with corresponding teeth *s⁵* adapted to engage the teeth *s⁴* and an axial stud or pintle *s⁶* projects therefrom and is adapted to engage the hole *s³*. When the spindle *S* is in its forward position, as illustrated in Fig. 1, its end will abut the end of the spindle-extension *S'* and engage the latter so that they both rotate as one. The screws *o*, through their engagement with the splines *s'*, cause the bushing *M* to rotate with the spindle-extension *S'* and through this arrangement the outer end of the spindle *S* is suitably supported to take the weight of the package and resist the pull of the twine as it is wound on to the tube *x* under tension. The spindle-extension *S'* is also susceptible of being drawn outward in the bushing *M* for a purpose later described. It is also to be noted that the tip end *s⁷* of the spindle *S* is slightly reduced in diameter 90 from that of the main portion and corresponds in diameter to the projecting end of the spindle-extension *S'*. This diameter is slightly less than that of the bore of the cop-tube *x* to provide that the ends of both 100 portions of the spindle will not stick or bind in the tube when the main spindle *S* is retracted as shown in Fig. 2.

The spindle *S* is screw-threaded from its opposite end throughout approximately one-half its length and, normally, the greater part of this threaded portion lies within the shaft *C*. It will also be observed by reference to Fig. 2 that this screw-threaded portion *s⁸* of the spindle *S* is formed with a key-way or spline *s⁹* which is engaged by a key *c'* secured in the end of the shaft *C*. This provides that the shaft *C* and spindle *S* will be rotated together from the driving pulley *E* to rotate the cop-tube *x* and wind 115 on the material.

A small portion of the threaded end of the spindle *S* projects from the end of the shaft *C* when its opposite end is in engagement with the extension *S'*, as shown in 120 Fig. 1, and at its extremity is secured a cap or collar *R* formed with a flange *r*. Normally, this flange *r* is engaged by the crescent-shaped extension *v* of a lever *V* which is formed with a pocket *v'* adapted 125 to receive the flange, see Fig. 3. This engagement acts to prevent the spindle *S* from sliding in the shaft *C* in either direction and maintains it in its normal position during the winding. The lever *V* is 130

also provided with a half-nut v^2 adapted to be carried into engagement with the threads on the spindle S to cause the retraction of the spindle within the shaft C, as more fully explained hereinafter. Referring to Fig. 2, it is to be noted that the spindle S is reduced in diameter at s^{10} so that the half-nut v^2 will ride on this portion of the spindle after the threaded portion has passed through the nut. Preferably the lever V is secured by a pin v^3 to the end of a rod or rock-shaft W mounted in bearings b^5 , b^6 in the main frame B of the machine. At its opposite end the rod W is bent at right-angles and extends upwardly between the winding spindle and cam-shaft to provide a handle w for operating the lever V manually. Collars w^1 and w^2 are secured to the rod W adjacent the bearings b^5 and b^6 to hold the rod from longitudinal movement and between the collar w^1 and the hub v^4 of the lever V is a coiled spring y. One end of the spring y is secured in a hole v^5 of the hub v^4 , see Fig. 2, and its opposite end extends through a hole b^7 in a rib b^8 which projects from the side of the frame B, see Fig. 3. The torsion of the spring y tends to rock the rod W and swing the lever V in the direction indicated by the arrow 2, Fig. 3, to carry the nut v^2 away from the spindle S. A pin z driven into the frame B limits the movement of the lever V in this direction and maintains it in position for the extension v to engage the flange r with a clearance between the periphery of the flange and the bottom of the pocket v^1 . This arrangement prevents the action of the spring y from causing the tension v' to bear against the periphery of the flange and cause undue wear on the engaging parts.

The operation of the whole machine is as follows: Before the commencement of the winding parts will be in a position as illustrated in Fig. 2. The cop-tube x, represented in Fig. 2 by dot-and-dash lines, is placed in position by first withdrawing the spindle-extension S' from its normal position. This is performed by grasping the hand-knob N and pulling it back against the action of the spring p, and the tube x can then be placed in position with one end resting on the tip end s^7 of the main spindle S, see Fig. 4. The knob N is then released to allow the spindle-extension S' to enter the opposite end of the tube as shown in Fig. 2. The handle w is next moved forward slightly to carry the lever V into a neutral position with the extension v clear of the flange r and the nut v^2 free from the threads on the spindle S. The spindle S can then be thrust forward through the shaft C and into the tube x until its end abuts the end of the spindle-extension S' with the pintle s^6 engaging the hole s^3 and

the teeth s^5 engaging the teeth s^4 to form practically one continuous shaft. The handle w is now released and the spring y will carry the lever V into position for the extension v to engage the flange r, as shown in Figs. 1 and 3. The sides of the extension v of the lever V abuts both sides of the flange r to maintain the spindle S from longitudinal movement and the machine is now ready for operation. The twine t is led up from its supply to the guide-arm L and drawn over the guide-rolls l' and l^2 whence it is fed to the winding spindle. After the end of the twine has been secured to the cop-tube x the belt is shifted from the loose pulley E' on to the driving pulley E and the machine starts to operate. The pulley E drives the shaft C, which, through the key c', rotates the spindle S, and the cop-tube is turned to wind on the material. Usually the tube x fits the spindle S so snugly that it will turn with it without the need of holding means, but, if required, suitable holding devices such as expanding springs or ribs might be provided to grip the interior of the tube.

The shaft D is driven from the shaft C through the pulleys F, G and belt g and the cam J rotates therewith to reciprocate the guide-arm L. The traverse of the guide-arm acts to deposit the coils of winding on the cop-tube x in superimposed layers and the package is built up to substantially the proportions illustrated by dot-and-dash lines in either Fig. 1 or Fig. 4.

When the package reaches its predetermined size and is ready to be doffed from the winding spindle the handle w is grasped by the operator and carried forward in the direction indicated by the arrow 3, Fig. 3. This brings the half-nut v^2 into engagement with the threads s^8 on the spindle S and the rotation of the latter will cause it to feed back through the nut in the direction indicated by the arrow 4, Fig. 2. The spindle S is thus retracted within the shaft C and during its movement the end of the sleeve c^2 engages the end of the cop-tube x and as the spindle S is withdrawn within the sleeve the latter acts to hold the tube until it is forced free of the main portion of the spindle and simply rests upon the reduced tip-end s^7 , see Fig. 2. The opposite end of the cop-tube x will still remain supported on the end of the spindle S' and in this way the package is prevented from falling on the floor and becoming damaged. After the screw-threaded portion of the spindle S has fed completely through the nut v^2 the latter will ride on the reduced portion s^{10} and no further movement of the spindle will be effected. The handle w can now be released and the driving belt is shifted on to the loose pulley E' to arrest the operation of the mechanism. To remove the package from the machine it

is now only necessary to pull out the hand-knob N, as shown in Fig. 4, to withdraw the spindle-extension S' from the outer end of the tube x and the opposite end of the cop-
 5 tube can then be drawn off the end of the spindle S. The ends of the spindle S and spindle-extension S' being of slightly less diameter than the bore of the tube x, as before explained, it will be seen that the tube
 10 will not pinch or bind at these points, but can be easily slipped off. After the doffing of the completed package the parts of the mechanism are in position to receive a new cop-tube which can be quickly applied as before explained.

It will be seen that my new device provides a convenient and easily operated means for applying the cop-tubes to the winding spindle and for automatically doffing the completed package without manual labor and without pressure against the ends of the package, thereby removing all danger of damage to the package itself or injury to the material of which it is composed.

25 Various modifications might be made in the structure and arrangement of the parts of my device without departing from the spirit or scope of my invention.

Therefore without limiting myself to the exact structure shown and described what I claim is:

1. In a winding or like machine, the combination, with a winding spindle adapted to enter the bore of the cop-tube for supporting and rotating the latter, of means operated through the rotation of the spindle to withdraw it from the bore of the tube.

2. In a winding or like machine, the combination with a winding spindle adapted to enter the bore of the cop-tube for supporting and rotating the latter, of means operated through the rotation of the spindle to withdraw it from the bore of the tube, and means to hold the tube during the withdrawal of the spindle.

3. In a winding or like machine, the combination with a winding spindle adapted to enter the bore of the cop-tube, of means operated through the rotation of the spindle to move the latter longitudinally to withdraw it from the tube, and stationary means engaging the end of the tube to hold the latter during the withdrawal of the spindle.

4. In a winding or like machine, the combination with the driving means therefor, of a winding spindle rotated thereby and adapted to enter the bore of the cop-tube, and manually operated means adapted to be thrown into position to cause the rotation of the spindle to withdraw it from the cop-tube.

5. In a winding or like machine, the combination with a rotating shaft having a telescopic spindle extending therefrom to enter the bore of the cop-tube to support the latter, and means operated through the rotation

of the shaft to telescope said spindle and shaft to withdraw the spindle from the bore of the cop-tube.

6. In a winding or like machine, the combination with a hollow shaft, of a spindle arranged to slide within the shaft and adapted to project therefrom to enter the bore of the cop-tube, and means operated through the rotation of the shaft to telescope the spindle within the shaft to doff the cop-tube therefrom.

7. In a winding or like machine, the combination with a rotatable shaft, of a spindle slideable longitudinally in relation to said shaft and adapted to enter the bore of the cop-tube, and means for causing the rotation of the shaft to slide the spindle to withdraw it from the bore of the cop-tube.

8. In a winding or like machine, the combination with a rotating spindle adapted to enter the bore of the cop-tube for supporting the latter, of means operated through the rotation of the spindle to move the spindle longitudinally to withdraw it from the bore of the cop-tube.

9. In a winding or like machine, the combination with a rotating spindle for supporting the cop-tube, of manually controlled means adapted to be engaged with the spindle to cause its rotation to move the spindle longitudinally to withdraw it from the cop-tube.

10. In a winding or like machine, the combination with a rotating spindle formed with screw-threads and having a portion adapted to support the cop-tube, of means to engage the screw-threads during the rotation of the spindle to move the latter longitudinally to withdraw it from the cop-tube.

11. In a winding or like machine, the combination with a rotating spindle formed with screw-threads and having a portion adapted to support the cop-tube, of a half-nut adapted to be engaged with said screw threads during the rotation of the spindle to move the latter longitudinally to doff the cop-tube.

12. In a winding or like machine, the combination with a rotating, hollow shaft, of a spindle slideable within said shaft and adapted to project therefrom to enter the bore of the cop-tube, means to cause the rotation of the spindle with the shaft, and means operated through the rotation of the shaft to telescope the spindle within the shaft to force the cop-tube off the spindle.

13. In a winding or like machine, the combination with a rotating hollow shaft, of a spindle slideable within said shaft and adapted to project therefrom to support the cop-tube, said spindle keyed to the shaft to cause it to rotate therewith and formed with screw threads throughout a portion of its length, and means to engage said screw

threads to cause the retraction of the spindle to withdraw it from the cop-tube.

14. In a winding or like machine, the combination with a hollow shaft mounted in fixed bearings, a driving pulley to rotate said shaft, a spindle slidable within the shaft and adapted to project therefrom to support the cop-tube, said spindle keyed to the shaft and formed with screw threads, means to normally hold the spindle from sliding in the shaft, and means to engage the screw-threads on the spindle whereby its rotation will cause it to be retracted within the shaft to withdraw it from the cop-tube.

15. In a winding or like machine, the combination with a rotating spindle for supporting the cop-tube, said spindle adapted to slide longitudinally and formed with screw-threads, of a lever adapted to be held in its normal position to restrain the spindle from sliding and to be moved into another position to engage the screw-threads and cause the spindle to slide to withdraw it from the cop-tube.

16. In a winding or like machine, the combination with a slidable, rotating spindle having one portion adapted to receive and support the cop-tube and another portion formed with screw-threads, of a flange on said spindle, and a rockable lever formed with an extension adapted to engage said flange to hold the spindle from sliding and also formed with a half-nut adapted to be engaged with the screw-threads on the spindle to cause the latter to slide to withdraw it from the cop-tube.

17. In a winding or like machine, the combination with a slidable rotating spindle having one portion adapted to receive and support the cop-tube and another portion formed with screw-threads, of a lever adapted in one position to engage the spindle to restrain it from sliding and in another position to engage the screw-threads to cause the spindle to slide, means to normally maintain the lever in its first position, and manually operated means to move the lever into its other position.

18. In a winding or like machine, the combination with a rotating hollow shaft, of a spindle slidable longitudinally within said shaft and formed with screw-threads, a key in said shaft engaging a spline extending along the spindle, a flange at the end of the spindle, a rockable lever having an extension formed with a pocket adapted to receive said flange, and a half-nut on said lever adapted to be engaged with the screw-threads on the spindle after the extension is disengaged from the flange.

19. In a winding or like machine, the combination with a slidable, rotating spindle S formed with screw-threads, of a rockable rod W having a handle w, a lever on

said rod having an extension adapted to normally engage the spindle to hold it from sliding, said lever also formed with a half-nut to engage the threads on the spindle to cause it to slide, and a spring to rock the lever and maintain it in its normal position.

20. In a winding or like machine, the combination with a spindle S rotatable in stationary bearings and having an overhanging portion adapted to receive and support the cop-tube, of means to slide the spindle longitudinally of its bearings to withdraw it from the cop-tube, a bearing beyond the outer end of the spindle, and a spindle-extension S' rotatable in said bearing and adapted to engage the end of the spindle S to support its overhanging portion.

21. In a winding or like machine, the combination with a spindle S rotatable in stationary bearings and having an overhanging portion adapted to receive and support the cop-tube, of means to slide the spindle longitudinally of its bearings to withdraw it from the cop-tube, a bearing beyond the outer end of said spindle S, and a spindle extension S' rotatable in said bearing and adapted to normally engage the end of the spindle S to rotate therewith and to be retracted in its bearing to allow the placing and removal of the cop-tube.

22. In a winding or like machine, the combination with a rotating spindle S having an overhanging portion adapted to support the cop-tube, said spindle formed with radial teeth s⁵ and an axially projecting pinte s⁶ at its end, of means to slide the spindle longitudinally to withdraw it from the cop-tube, and a live spindle-extension S' supported in axial alinement with the spindle S and having its end formed with teeth s⁴ adapted to engage the teeth s⁵ and an axial hole s³ for receiving the pinte s⁶.

23. In a winding or like machine, the combination with a slidable rotating spindle S having an overhanging portion for supporting the cop-tube, of means to normally hold said spindle in its forward position, means to retract said spindle longitudinally to withdraw it from the cop-tube, a spindle-extension S' adapted to rotate in axial alinement with said spindle S and to engage its end, a spring to maintain the spindle-extension in engagement with the spindle S, and means to retract said spindle-extension against the action of the spring.

24. In a winding or like machine, the combination with a slidable rotating spindle S having an overhanging portion for supporting the cop-tube, of means to slide the spindle longitudinally to withdraw it from the cop-tube, an outboard bearing located beyond the end of said spindle, a bushing rotatable in said bearing in axial 120 125 130

alinement with the spindle S, a spindle-extension S' rotatable with said bushing and slideable therein, a spring to slide said spindle-extension forward to maintain its end in engagement with the spindle S, and a hand-knob for retracting the spindle-extension in the bushing against the action of the spring.

In testimony whereof I affix my signature in presence of two witnesses.

EVERETT C. LEWIS.
